UNITED STATES PATENT OFFICE.

FRED BURKS AND CHARLES ROHLFS, OF BUFFALO, NEW YORK.

ELECTRICAL APPARATUS.

SPECIFICATION forming part of Letters Patent No. 768,581, dated August 30, 1904.

Application filed January 28, 1904. Serial No. 190,965. (No model.)

To all whom it may concern:

Be it known that we, FRED BURKS and CHARLES ROHLFS, citizens of the United States, and residents of Buffalo, in the county of Erie 5 and State of New York, have invented a new and useful Improvement in Electrical Apparatus, of which the following is a specification.

This invention relates more particularly to an electrical apparatus comprising an electric-current-generating machine contained in or supported by a dumb-bell or other portable device adapted for exercising purposes and operated to produce the current by the manipulation of the container and electrical connections for transmitting the current generated by the machine to the person using the apparatus.

The object of the invention is to provide an apparatus of attractive and pleasing character and of simple, durable, and inexpensive construction, suitable both for exercising and therapeutical purposes.

In the accompanying drawings, Figure 1 is a sectional elevation of an apparatus embodying the invention. Fig. 2 is a sectional elevation of the bell containing the generating-machine in line 2 2, Fig. 1. Fig. 3 is a horizontal section, partly in plan, on an enlarged scale, in line 3 3, Fig. 2. Fig. 4 is a fragmentary sectional elevation in line 4 4, Fig. 3.

Like letters of reference refer to like parts in the several figures.

A represents a portable device, preferably in the form of a hollow dumb-bell, having enlarged balls or heads α α' , connected by a central tubular handle or shank. The bell constitutes a container for the electric-current-generating machine and a motor for driving the same and also an electrode for conveying the current to the hand of the person using the apparatus, and for this reason the bell is preferably made of metal to give an extended contact-surface for the hand; but, as will be manifest, the bell could be made of wood or other insulating material and provided with a metal handle or contact-plate for the hand at any suitable point.

An electric-current-generating machine is mounted in the head α of the dumb-bell, which

is provided in the construction shown in the drawings with blocks b of wood or other insulating material, for supporting the generating-machine and insulating the same from the metal portions of the dumb-bell. A magneto-electric machine is shown, consisting of a permanent horseshoe-magnet C, arranged and held between the wooden insulating-blocks b and an armature D, which is arranged, as usual, between the opposite poles of the magnet and supported on an armature-shaft d , which is provided at one end with a journal entering a bearing-hole in the bent end of the magnet and at the other end with a journal entering a hole in a bearing-plate d' , which spans the ends of the magnet, to which it is secured by screws or in any other suitable manner. The armature is provided with the usual winding, connected at one end to the armature and at the other end to the usual insulated collector-ring e .

The armature of the magneto-electric machine is rotated to generate the current by a motor, which in the construction illustrated consists of a weight F, confined loosely in and adapted to reciprocate longitudinally in the shank of the dumb-bell. The weight is reciprocated from end to end of the shank by alternately inverting and righting the dumb-bell, and this movement of the weight is transmitted to the armature-shaft to rotate the armature by suitable connections, such as a belt or cord G, attached at its two ends to the opposite ends of the movable weight and passing into the head α , containing the generating-machine, around a pulley h on the armature-shaft, and around a tensioning pulley or sheave H, mounted in the other head, α' , of the dumb-bell. The intermediate portion of the belt passes freely through a longitudinal hole h' in the weight. The belt is moved back and forth by the reciprocating movements of the weight and turns the armature-shaft and armature alternately in opposite directions, thus producing a current.

The tensioning pulley or sheave is preferably journaled in an adjustable yoke or frame i , which is connected by an adjusting-screw i' with a stationary frame k , secured in the

head a' of the dumb-bell. The stationary frame is preferably of U shape and is fixed by screws i^2 in the end of the shank which extends into the head a' . The upper ends of 5 the legs of the U-frame are bent downwardly beside the sheave-yoke to hold the latter from turning. The head of the dumb-bell is provided opposite the end of the adjusting-screw with a hole k^2 , through which a screw-driver 10 can be inserted and engaged with the adjusting-screw, for turning the same. This construction affords a convenient means for adjusting the tensioning pulley or sheave to properly tighten or slacken the driving belt 15 or cord.

l^1 l^2 represent yielding buffers or springs which are secured in the opposite ends of the shank of the dumb-bell to receive the impact of the weight and lessen the effect of the 20 cushion and shock on the hand.

While a belt or cord is described for transmitting the motion of the weight to the armature-shaft, other transmitting connections could be employed. The belt or cord, however, is an inexpensive and desirable connection. Furthermore, the invention is not limited to the use of the weight-motor described for driving the generating-machine, but comprehends the use of other motors which are 30 operated or set in operation by the manipulation of the container.

The dumb-bell containing the generating-machine, which will hereinafter be termed the "container," constitutes an electrode and is 35 connected to one terminal of the machine in any convenient manner—for instance, by a contact plate or brush M , secured to one of the supporting-blocks b for the magnet, with one end bearing against the collector-ring on 40 the armature-shaft and the other end contacting with the metallic head of the container.

P represents a second electrode, connected to an insulated conducting-wire p , which enters the head a of the container and is connected 45 in any suitable manner to the other terminal of the generating-machine. The electrode P , which will hereinafter be called the "electrode" to distinguish it from the container, is preferably of the same shape, size, and weight 50 as the container to create the impression of being a duplicate container, provided with a generating-machine, and for this purpose a sliding weight Q , similar to the weight for operating the generating-machine, is loosely 55 confined to reciprocate in the shank of the electrode, which is provided with yielding buffers or springs at the opposite ends of the shank to relieve the jars incident to the operation of the weight. The electrode may be in 60 the form of a hollow metal shell like the container or may be made of insulating material provided with a metal contact plate or portion. When the electrode is held in one hand and the container in the other hand and both devices

manipulated, the reciprocating weights in the 65 two devices produce like impacts or jars on the container and electrode, thus creating the impression that each contains a generating-machine.

In using the apparatus the user holds the 70 container and electrode in his two hands and manipulates the same in such manner as to reciprocate the weights, thus driving the generating-machine as before explained, and a current is generated which traverses the circuit completed through the container and electrode, the conductor connecting the same and the arms and body of the person using the apparatus. 75

Instead of the hand-electrode P the conducting-wire could be connected with an electrode of any sort adapted to be placed in contact with any desired portion of the person's body. 80

The magneto-electric machine is preferably provided with a rheotome or circuit-interrupter. The interrupter shown is of known construction, consisting of a star-wheel r , which is secured to the armature-shaft of the generator and in the rotation of the shaft intermittently contacts with a spring-plate r' , 90 which is connected to or formed integrally with the contact-plate M , connecting with the collector-ring of the generator. The rheotome operates in a well-known manner to interrupt and intermittently short-circuit the current 95 through the machine for raising the electro-motive force of the current in the external circuit and intensifying its effect on the person, thereby enabling the use of a small machine generating a relatively feeble current 100 and also better adapting the apparatus for therapeutic purposes.

A dynamo-electric machine could be substituted for the magneto-electric machine shown; but the latter is preferred, because a 105 small machine with a permanent magnet of good quality will produce a stronger current than a dynamo-electric machine of substantially the same dimensions and is also cheaper than a dynamo-electric machine. 110

We claim as our invention—

1. In an apparatus of the character described, the combination of a container, an electric-current-generating machine in said container, and means in said container and operated by the manipulation of the latter to drive said generating-machine, substantially as set forth. 115

2. In an apparatus of the character described, the combination of a container, an electric-current-generating machine in said container, a motor in said container and operated by the manipulation of the container, and connections between the motor and generating-machine for operating the latter, substantially 120 as set forth. 125

3. In an apparatus of the character described, the combination of a container, an elec-

tric-current-generating machine in said container, and a device in said container operated by gravity when said container is inverted to drive said generating-machine, substantially 5 as set forth.

4. The combination of a device to be held in the hand and manipulated, an electric-current-generating machine supported by said device, means supported by said device and operated 10 by the manipulation of the latter for driving said generating-machine, and electric connections for transmitting the electric current to a person, substantially as set forth.

5. The combination of a device constituting 15 an electrode to be held in the hand and manipulated, an electric generating-machine supported by said device, a motor supported by said device and operated by the manipulation of the same, connections between said motor 20 and said generating-machine for operating the latter, an electrode, and electrical connections for the current between said device and electrode, substantially as set forth.

6. The combination of a container in the 25 form of a dumb-bell, an electric-current-generating machine arranged in one head of the container, a reciprocating motor arranged in the shank of said container, connections between said motor and generating-machine for 30 operating the latter, and conducting means for the current produced by said generating-machine, substantially as set forth.

7. The combination of a hollow container having a head, and a shank, an electric-current-generating machine arranged in the head of said container, a reciprocating weight arranged to slide in the shank of said container and which is reciprocated by the manipulation 35 of the container, and connections between 40 said weight and the armature of said generating-machine for operating the latter, substantially as set forth.

8. The combination of a container having a hollow head and a tubular shank, an electric-current-generating machine mounted in said head, a weight arranged to slide in said tubu- 45

lar shank and adapted to be reciprocated by the manipulation of said container, a pulley on the armature-shaft of said generating-machine, a pulley mounted in said container, and a belt attached to said weight and passing around said pulleys to drive the armature, substantially as set forth. 50

9. The combination of a container having a hollow head and a tubular shank, an electric-current-generating machine mounted in said head, a weight arranged to slide in said tubular shank and adapted to be reciprocated by the manipulation of said container, a pulley on the armature-shaft of said generating-machine, a tensioning-pulley movably mounted in said container, a belt attached to said weight and passing around said pulleys for driving the armature, and means for adjusting said tensioning-pulley, substantially as set 60 forth. 65

10. The combination with a container, an electric-current-generating machine, and a reciprocating motor for operating the same inclosed in said container, of an electrode in 70 electrical connection with said generating-machine, said electrode containing a reciprocating weight, substantially as set forth.

11. The combination with a container in the form of a dumb-bell, an electric-current-generating machine inclosed in said dumb-bell, a weight arranged in the shank of said dumb-bell, and connections from said weight to said generating-machine for operating the latter, of an electrode in the form of a dumb-bell 75 electrically connected with said generating-machine and provided with a weight adapted to slide in the shank thereof, substantially as set forth.

Witness our hands this 25th day of January, 85 1904.
